(57) **CLAIM**

The ornamental design for a landscape edger with scallop features as shown and described.

DESCRIPTION

FIG. 1 is a top front right three-dimensional view of a landscape edger with scallop features showing my new design;

FIG. 2 is a bottom back left three-dimensional view of the landscape edger with scallop features of FIG. 1;

FIG. 3 is a front view of the landscape edger with scallop features of FIG. 1;

FIG. 4 is a back view of the landscape edger with scallop features of FIG. 1;

FIG. 5 is a left view of the landscape edger with scallop features of FIG. 1;

FIG. 6 is a right view of the landscape edger with scallop features of FIG. 1;

FIG. 7 is a top view of the landscape edger with scallop features of FIG. 1; and,

FIG. 8 is a bottom view of the landscape edger with scallop features of FIG. 1.

The broken lines in the drawings depict portions of the landscape edger with scallop features that form no part of the claimed design.

1 Claim, 5 Drawing Sheets
